DESIGN FOR A WASHING MACHINE

John McLeod Little, Toledo, Ohio, assignor to
Federal Telephone and Radio Corporation, New
York, N. Y., a corporation of Delaware

Application October 28, 1947, Serial No. 142,165

Term of patent 14 years

(Cl. D49—1)

To all whom it may concern:

Be it known that I, John McLeod Little, a citizen of the United States, residing at 3456 Beechway Boulevard, Toledo, Ohio, have invented a new, original, and ornamental Design for a Washing Machine, of which the following is a specification, reference being had to the accompanying drawing, forming part thereof.

Fig. 1 is a perspective view of a washing machine taken from the left-hand side thereof, embodying my new design; and

Fig. 2 is a perspective view taken from the right-hand side thereof.

The characteristic features of my design reside in the portions shown in solid lines.

I claim:

The ornamental design for a washing machine, substantially as shown and described.

JOHN MCLEOD LITTLE.
